UNITED STATES PATENT OFFICE.

HENRY GEISENHÖNER, OF SCHENECTADY, NEW YORK, ASSIGNOR TO
GENERAL ELECTRIC COMPANY, A CORPORATION OF NEW YORK.

TIME-SWITCH.

No. 829,774.

Specification of Letters Patent.

Patented Aug. 28, 1906.

Application filed August 24, 1905. Serial No. 275,573.

To all whom it may concern:

Be it known that I, HENRY GEISENHÖNER, a citizen of the United States, residing at Schenectady, county of Schenectady, State of New York, have invented certain new and useful Improvements in Time-Switches, of which the following is a specification.

This invention relates to cut-outs for electric circuits, and has for its object the provision of a device which will operate automatically, is simple in construction, easy to manipulate, and at the same time thoroughly reliable, safe, and efficient.

More specifically, my invention relates to time-switches for cutting translating devices in and out of circuit when the same have been in operation for a definite period.

In carrying out my invention I provide a switch in which the movable element consists of a quantity of mercury and which has a bias to open position. Upon closing the switch an electromagnetic device is energized which maintains it in a closed position for a definite time, which time is controlled by the passage of mercury from one part of the moving element to the other. A retarding means is provided which is made adjustable, so as to vary the time consumed by the mercury in passing. When the mercury reaches a definite level, the electromagnetic device is short-circuited, allowing the movable controlling element to assume its normal open position.

My invention further consists in the features of construction and in the arrangement and combination of elements hereinafter set forth, and particularly pointed out in the claims annexed to and forming a part of this application.

In the drawings, Figure 1 is a plan view of a device embodying my invention. Fig. 2 is a plan view of the same with the movable element removed. Fig. 3 is a section on the line of 3 3 of Fig. 2, the removable element being shown in elevation and in the open position. Fig. 4 is a similar view with the movable element shown in closed position. Fig. 5 is a sectional view of the movable element on the line 5 5 of Fig. 3, and Fig. 6 is a diagram of the circuit connections.

Referring to the drawings, 10 is the base of a switch and may be of any suitable material, preferably, however, of some insulating ma-

terial, such as wood or hard rubber. Pivotally mounted at 11 is the movable or controlling element of the switch 12. This movable element is made hollow, so as to contain a quantity of mercury. In the particular construction shown this element is cast with two communicating chambers 13 and 14 and having a flanged or circular base 15. The particular form, however, of this element and the material thereof is no part of my invention and may be varied at will. For convenience in casting and for inserting the mercury the chambers 13 and 14 are left open at one end and afterward provided with plugs 16 and 17. Plug 16 is merely a flat piece of material for closing the chamber and retaining the mercury therein. Plug 17, however, extends to substantially the middle of the chamber 13 and is provided with a passage therethrough, 18, having its inner end funnel-shaped, as at 19, and a portion 20 at right angles to the passage 18 for communicating with chamber 14. The wall 21, separating the two chambers, is provided with a passage 22, which coincides with the passage 20, allowing free communication between the chambers. The wall is also cut 80 away at 23 to form an air-passage between the chambers. The screw 24 is threaded into the boss 25 in the wall of the chamber 14 and is provided with a conical tip 26. This screw is opposite the communicating passage, and by adjusting the same the passage may be restricted more or less, as desired, to vary the time consumed by the mercury in passing from one chamber to another. The base 10 is cut away to form a shouldered support 27 for the disk 28 of insulating material. This disk is secured to the base and provides a support for the member 12, which is pivoted thereto by means of a screw 29. The member 12 is biased to the open position, which is the position shown in Figs. 1 and 3, by means of spring 30, coiled about the screw 29 and having one end anchored in the member 12, the other in the disk 28. A ring 31, of magnetic material, is pivotally mounted on the pins 32 and 33, secured to the disk 28, so that one side rests upon core 35 of an electromagnet 36, inserted in the disk, so that its upper face is flush with the surface of the disk. This magnet is held in place by means of a supporting-arm 37, se-

cured to the screw 29. The opposite side of the ring 34 is provided with a conical projection 38, which fits into the depression 39 in member 12 and which comes opposite the 5 projection when the member is in its closed position, as shown in Fig. 4. The ring then locks the member in closed position when the magnet 36 is energized to hold the portion 34 of the ring down, and consequently the projection 38 up into the depression 39. The disk 28 is provided with contact-clips 40, 41, 10 42, and 43, and contact-screws 42' and 43', forming terminals for circuits, as hereinafter described, are mounted on but insulated 15 from member 12. The member 12 also is provided with contact 44 for bridging the fixed contacts.

The operation of my device is as follows: With the switch in the position shown in Figs. 20 1 and 3 the circuit is open and no current therefore passes. When, however, the element 12 is turned through ninety degrees by means of a handle 45, the contact 44 bridges the clips 40 and 41 and the screws 42' and 25 43' contact with clips 42 and 43, respectively, as shown in dotted lines in Fig. 6. The current then passes from main 46 through bridging contact 44, conductor 47, through the translating devices, which may be heaters or 30 lamps, thence from conductor 49 to contact 43, through magnet 36 to contact 42, back to the line at 49. This condition remains as long as the magnet 36 is energized. In the meantime, the member 12 having been rotated, the 35 mercury which was in the chamber 13 when it was horizontal flows through the communicating passage into the chamber 14, both chambers now being vertical. The mercury will of course rise until the level is 40 the same in both chambers. When the mercury reaches the contact-screws 42' and 43', which have terminals projecting into the interior of the chamber, the magnet 36 will be short-circuited, releasing the ring 34, and 45 hence the member 12, which will be returned to the open position by the spring 30. The circuit is thus opened, the time during which it is closed being regulated by the screw 24. When the member returns to its normal position, the chambers being horizontal, the 50 mercury returns through the passages to the lower chamber 13.

It will thus be seen that I have provided a simple and efficient time-switch which may 55 be regulated and adjusted so as to automatically open or close the circuit of the translating device after a predetermined interval. A very important feature of my invention is that the circuit is never opened at the mercury-contact while the terminals are alive, and therefore there can be no arcing, and the mercury does not develop troublesome and dangerous arcs. When the time-limit expires, the mercury closes a shunt of low 60 65 resistance around the retaining-magnet, and

thus no arc can occur, as the circuit is broken at the switch-clip.

This device finds a ready application in connection with electric heaters which it is desired shall operate for a definite period and 70 then open circuit. It is, however, not limited in its application to uses of this character, since many other applications will suggest themselves to those skilled in the art.

What I claim as new, and desire to secure 75 by Letters Patent of the United States, is—

1. A time-switch for electric circuits comprising a movable mercury-receptacle adapted to close an electric circuit but having a bias to open position, electrically-controlled 80 means for retaining said receptacle in closed position, and means controlled by the mercury for releasing the same after a predetermined time.

2. A time-switch for electric circuits 85 comprising a pivoted spring-returned receptacle containing mercury, means in connection with said receptacle for closing an electric circuit against the tension of the spring, electrically-controlled means for retaining the 90 same in closed position, and means controlled by the flow of mercury from one part to another of said receptacle for deenergizing said device to release said receptacle.

3. A time-switch for electric circuits 95 comprising a pivoted receptacle containing mercury and adapted to close an electric circuit but having a bias to open position, an electrically-controlled device for retaining said receptacle in closed position, and means controlled by the mercury for deenergizing said device to release said receptacle.

4. A time-switch for electric circuits comprising a pivoted spring-returned receptacle containing mercury and adapted to close an 105 electric circuit, an electrically-controlled device for retaining the same in closed position, means for retarding the flow of mercury within said receptacle when the latter is moved to close the circuit, and means controlled by the 110 flow of mercury for deenergizing said device to release said receptacle.

5. A time-switch for electric circuits comprising a pivoted spring-return receptacle provided with communicating compartments 115 and containing mercury, means in connection with said receptacle for closing an electric circuit against the tension of the spring, an electromagnetic device for retaining the receptacle in close-circuited position, and means whereby said device is short-circuited when the mercury reaches a predetermined level in one of said compartments.

6. A time-switch for electric circuits comprising a pivoted spring-return receptacle 125 provided with communicating compartments and containing mercury, means in connection with said receptacle for closing an electric circuit against the tension of the spring, an electromagnetic device for retaining the 130

same in closed position, means for retarding the flow of mercury from one compartment to another when the receptacle is moved to close the circuit, and means whereby said device is deenergized to release the receptacle when the mercury reaches a predetermined level in said latter compartment.

In witness whereof I have hereunto set my hand this 23d day of August, 1905.

HENRY GEISENHÖNER.
